TWO-PIECE INSULATED CONTAINER HAVING AN OPEN END

Edward R. Jereore, 23030 Shoreview,
St. Clair Shores, Mich. 48082

Filed Feb. 23, 1965, Ser. No. 83,925

Term of patent 3½ years

(Cl. D58—17)

Fig. 3

Fig. 4

Fig. 5

FIGS. 1 and 3 are perspective views from the front and rear, respectively, of a two piece insulated container having an open end embodying my invention;

FIG. 2 is an exploded perspective view thereof partly in section showing the top separated from the bottom of the container;

FIGS. 4 and 5 are sectional views of the design of FIG. 1 taken, respectively, on the lines 4-4 and 5-5 thereof.

I claim:

The ornamental design for a two piece insulated container having an open end, as shown and described.
